(57) **CLAIM**

The ornamental design for a pair of connectors for a cord set, as shown and described.

DESCRIPTION

FIG. 1 is a front perspective view of the female member of the pair of connectors for a cord set according to the present invention;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and

FIG. 7 is a bottom plan view thereof.

FIG. 8 is a front perspective view of the male member of the pair of connectors for a cord set according to the present invention;

FIG. 9 is a front elevational view thereof;

FIG. 10 is a rear elevational view thereof;

FIG. 11 is a left side elevational view thereof;

FIG. 12 is a right side elevational view thereof;

FIG. 13 is a top plan view thereof; and,

FIG. 14 is a bottom plan view thereof.

The broken lines are included for the purpose of illustrating portions of the connectors that form no part of the claimed design.
